CHARLES SEYMOUR McFARLANE, OF AUCKLAND, NEW ZEALAND.

ROTARY PUMP FOR GAS-PRODUCING APPARATUS.

1,153,235.

Specification of Letters Patent. Patented Sept. 14, 1915.

Application filed January 12, 1912. Serial No. 670,872.

To all whom it may concern:

Be it known that I, CHARLES SEYMOUR McFARLANE, subject of the King of Great Britain, residing at 24 Swanson street, 5 Auckland, in the Dominion of New Zealand, have invented new and useful Improvements in Rotary Pumps for Gas-Producing Apparatus, of which the following is a specification.

10 This invention relates to apparatus for the production of gas in the form of carbureted air for heating and illuminating purposes by mixing petrol or other volatile hydrocarbon oils with air in the correct relative proportions.

15 The invention refers to apparatus of that class in which the power necessary for operating the mechanical feeding devices is derived from the gradual falling of a weight, 20 such operation being so governed by the apparatus that it will respond to the demands made upon the gas supply and automatically commence or suspend production.

25 The object of the present invention is the provision of a simple and reliable apparatus of this nature in which special means are provided to maintain a constant and regular supply of oil in the correct relative proportion to that of the air irrespective of the 30 consumption while by means of a specially devised carbureter a thorough evaporation of oil is attained.

35 In order that the nature of the invention and its construction may be fully understood, reference will now be made to the accompanying sheet of drawings in which:—

40 Figure 1— is a sectional elevation illustrating the apparatus as a whole. Fig. 2— is a sectional elevation of the pump wheel. Fig. 3— is a detail view of the oil elevator, and Fig. 4— is a horizontal sectional view of the carbureter showing one of the disks in place.

45 1 is a horizontal spindle having a drum or reel 2 upon which is adapted to be wound a cord 3. One end of the cord 3 is attached to the reel 2 while the other end is maintained in tension by means of a suitable weight 4 so that the falling of such weight 50 will have the effect of rotating the spindle

1. A suitable handle or crank 5 is provided to enable the reel to be turned for the purpose of winding the cord while to avoid a reverse rotation of the spindle 1 during such winding operation a ratchet or free-wheel 55 device may be interposed between such spindle and the reel 2.

Keyed upon the spindle 1 so as to be rotated thereby, is a drum or wheel 6 adapted to act as a pump to provide the necessary 60 supply of air. The said wheel which is immersed in water to a point above its axis (as indicated by the line A—A) comprises a hollow hub or boss 7 provided at either end with disks or faces 8 of suitable diameter. A plurality of arms or vanes 9, of a width corresponding with the interval between the disks 8 radiate at equal intervals around the boss 7, while the peripheries of the disks 8 are united by a suitable rim 10 65 so as to provide a series of pockets 11 (see Fig. 2). Holes or apertures 12 are provided through the rim 10 at the forward portion of each of the said pockets and holes 13 are also provided to give access between each of 70 the pockets and the interior of the boss. When the wheel is revolved in the proper direction as indicated by the arrow, each of the apertures 12 will in turn be carried beneath the surface of the water thus preventing 75 the escape of the air which filled the pocket when such was in the uppermost position. As the wheel continues to revolve the pocket becomes more and more submerged and consequently fills with water 80 thus expelling the air which passes through the holes 13 into the cavity of the boss 7.

85 The air passes from the boss 7 through the air delivery pipe 14 the entrance of which is arranged within the said boss at a point 90 above the water level. A vent or vents 15 are provided to permit of the escape of water from the boss.

95 The oil is contained in a reservoir 16 from whence it is conveyed to the oil delivery pipe 17 by means of the elevator 18. The said elevator comprises a disk or wheel 19 mounted upon a horizontal axis 20. Upon one side of the disk 19 is formed a ledge member 21 having a grooved channel formed 100

in the inner face thereof (see Fig. 3) and which ledge commences at a point near the periphery of the disk and continues in spiral or volute form to a point near the center at 5 which point a pipe 22 or other means are arranged to provide communication with the oil chamber 23 which in turn discharges into the oil delivery pipe 17. Instead of a single channel 21 as here shown, the disk may 10 be provided with two or more of such channels each arranged in the manner described in order that greater regularity of feed may be obtained. The oil elevator 18 is operated from the main spindle 1 through chain or 15 other suitable gearing 24 in order that the supplies of oil and air may be at all times in the same relative proportions. As the wheel or disk is rotated in the correct direction, the outer convolutions will collect a 20 certain amount of oil which, as the turning is continued will gradually flow around in such volute channel until the center is reached, at which point the oil from the innermost convolution flows through the pipe 25 22 into the duct 23. It will be seen that in this arrangement the oil simply flows by 30 gravity throughout the whole operation, the turning of the disk merely, as it were, serving to keep the channel in an incline in order that the oil may be caused to travel to the point of discharge at the center.

The mixing chamber or carbureter comprises a vessel 25 of cylindrical or other suitable form into the top of which the oil delivery pipe is introduced while the air delivery pipe enters such chamber near the lower end.

Within the vessel 25 are a plurality of 40 disks 26 of such diameter as to fit closely within the walls of such vessel and supported at the desired intervals apart by means of a central rod 27. Each of the said disks (see Fig. 4) is formed with perforations 28 while its periphery is notched 45 or serrated.

Arranged around the periphery of each of the disks so as to lie within the serrations is a quantity of calking-cotton or other absorbent material 29 the portions of such material above and below the disks 26 being 50 drawn together and bound to the rod 27 thus forming a series of cones as shown in Fig. 1.

The oil enters the chamber from the pipe 17 and drips upon the perforated dish or 55 plate 30 and thence upon the absorbent material below, while the air entering from the pipe 14 and in passing upward through the saturated material evaporates the oil and so forms the carbureted air which is led off 60 through the supply pipe 31.

By employing a disk, upon one of the side faces of which is carried a spiral ledge having a concave surface throughout upon its side facing inward or toward the center of

the disk, the quantity of liquid discharged 65 at the central outlet can never exceed the amount that can be contained within the said concave of the ledge, as instead of compressing, as in the case of rotary pumps, the surplusage of liquid, on reaching the inner 70 convolutions, will drip over the free edge of the ledge and so find its way back into the reservoir. Thus the present device will always supply a definite quantity of liquid for a given speed of rotation irrespective of 75 the depth of its immersion in the reservoir. In addition to this, however, the above action of the device in raising and allowing the liquid to drip back will also serve to agitate such liquid in the reservoir and so prevent 80 it from settling in layers according to the various specific densities of its components as might be the case if such were allowed to remain at rest.

I claim:

1. In an apparatus of the character described, in combination, a liquid reservoir, a vertical member rotatable on a horizontal axis adapted to be partially immersed in the fluid in said reservoir, a coiled grooved member projecting laterally from said rotatable member and movable therewith, and having the convolutions of said grooved member in the same vertical plane, and a conduit associated with the inner end of 90 said coiled groove whereby the liquid in said reservoir is conveyed to said conduit when said rotatable member is actuated, in a constant quantity proportional to the speed of rotation of the grooved member up to the 95 limit of the capacity of the latter and to discharge excess thereof over and into the reservoir as and for the purpose described.

2. An apparatus of the character described, having in combination, a reservoir 100 adapted to contain fluid, an elevator adapted to convey the fluid therefrom said elevator comprising a single disk mounted to rotate upon a horizontal axis and adapted to be partially immersed in the fluid in said reservoir, a substantially horizontal ledge mounted on one side of said disk and being formed with a grooved channel, said ledge commencing near the periphery of the disk and continuing in a volute form to a point near the center of said disk with the convolutions of said ledge spaced from each other and in the same vertical plane, fluid conveying means connected with the inner end of said channel for conveying the fluid therefrom.

3. In an apparatus of the character described, in combination, a liquid reservoir, means for feeding the liquid through said reservoir with equal and at a constant pressure and volume comprising a disk partially immersed in said reservoir, a rotatable coiled grooved member having the convolutions thereof spaced apart, said convolutions be-

ing disposed substantially horizontally and in the same vertical plane and secured to the side of said disk, conduit means associated with the inner end of said coiled grooved member for conducting the liquid in said reservoir therefrom, and means for rotating said disk.

In testimony whereof I have signed my name to this specification in the presence of two subscribing witnesses.

CHARLES SEYMOUR MCFARLANE.
